UNITED STATES PATENT OFFICE.

ULYSSES S. DE NURE, OF NEW YORK, N. Y., ASSIGNOR TO UNION SPECIAL MACHINE COMPANY, OF CHICAGO, ILLINOIS, A CORPORATION OF ILLINOIS.

RETAINER FOR SEWING-MACHINES.

1,324,543.

Specification of Letters Patent.

Patented Dec. 9, 1919.

Application filed January 30, 1917. Serial No. 145,488.

To all whom it may concern:

Be it known that I, ULYSSES S. DE NURE, a citizen of the United States, residing at New York, in the county of New York, 5 State of New York, have invented certain new and useful Improvements in Retainers for Sewing-Machines, of which the following is a description, reference being had to the accompanying drawing and to the figures of reference marked thereon.

The invention relates to new and useful improvements in retainers for sewing machines, and more particularly to a stationary retainer for holding one of the stitching threads in proper position to insure stitch formation.

Prior to the invention, stationary retainers of the above character have been used, but it has been customary to mount these 20 stationary retainers on the under surface of the throat plate. As a result of this construction, when adjusting the retainer for varying its relation to the stitch forming implements, it was necessary to remove the 25 throat plate and this made it very difficult to secure a proper positioning of the retainer.

An object of the present invention is to provide adjustable means for supporting a 30 stationary retainer, which means is entirely independent of the throat plate so that the throat plate of the machine may be removed for the purpose of viewing and adjusting the 35 retainer relative to the stitch-forming implement with which it coöperates without disturbing the relation of the retainer to said implement.

In the drawings:—

Figure 1 is a view, partly in front elevation and partly in section, showing a portion 40 of a sewing machine having my improvement applied thereto;

Fig. 2 is a view in top plan showing the work support with the throat plate removed so that the retainers and loopers may be 45 viewed when the former are being adjusted;

Fig. 3 is a view, partly in end elevation and partly in section, showing a portion of a machine having my improved retainer support applied thereto;

Fig. 4 is a view, partly in section and partly in perspective, showing a portion of

the work support and the support for the retainers;

Fig. 5 is a sectional view on the line 5—5 of Fig. 4;

Fig. 6 is an enlarged sectional view 55 through a portion of the work supporting apron and through the retainer support, showing the manner of adjustably supporting the retainer on its support;

Fig. 7 is a detail in side elevation, showing a modified form of retainer support;

Fig. 8 is a top plan view of the same;

Fig. 9 is a view, partly in section and partly in end elevation, of a different form 65 of work support and a different way of supporting the retainer support;

Fig. 10 is a top plan view of the same;

Fig. 11 is a view showing, more or less diagrammatically, the loopers, the needles and the retainers, the loopers having entered the needle loops and retracted to the position where the retainers are holding the needle loops back to insure the needles passing in front of both needle loops.

The invention is directed broadly to a stationary retainer for holding one of the stitching threads in proper position to insure stitch formation. The retainer must be supported so as to properly coöperate with the stitch-forming elements, and it is essential that the stationary retainer shall be set in just the right position so as to properly perform its function. When this retainer coöperates with the stitch-forming elements 80 beneath the throat plate it is difficult to properly adjust the retainer relative to the stitch-forming elements unless the retainer be so mounted or supported that the throat plate may be removed to expose to view the 85 adjusting means for the retainer and without disturbing the relation of the retainer to the stitch-forming element with which it co- 90 operates.

In the present embodiment of the invention, the retainer is used in connection with a two-needle stitching mechanism wherein a single looper coöperates with both needles, and wherein it is desired that both needles shall enter the thread triangle in advance of both needle loops. The retainer is located below the throat plate and is so po- 95 100

sitioned relative to the looper as to engage and hold back on the looper the needle loops until after the points of the needles have passed into the triangle in advance of the 5 needle thread loops. In order that this stationary thread retainer may properly co-operate with the looper, it must be set with great accuracy. Retainers of this character prior to my invention have been used, but it 10 has been the practice to support these retainers on the throat plate and when the throat plate has been removed so as to permit adjustment of the retainers, then the 15 thread retainers are removed from their co-operative relation to the looper, and it is extremely difficult to determine the proper amount of adjustment for the retainers to bring about the co-operation desired.

The present invention is directed to the 20 means for supporting these thread retainers which consists in supporting said thread retainers on a member which is independent of the throat plate so that, when the throat plate is removed, the retainers will be visible 25 to permit the adjustment of their relation to the looper, and the adjusting means which is readily accessible can be manipulated for bringing about a proper setting of the retainer relative to its looper.

30 Referring more in detail to the drawings:—

I have shown my improved support for the thread retainers as applied to the control of the needle thread loops in a sewing 35 machine which has a work support 1, and an overhanging arm 2, in which a needle bar 3 reciprocates, carrying two pairs of needles 4—4 and 5—5. Coöperating with the pair of needles 4—4 beneath the work support is 40 a looper 6. Coöperating with the pair of needles 5—5 beneath the work support is a looper 7. These loopers 6 and 7 are mounted on a looper carrier 8 which is pivoted to a looper rocker 9, and the looper carrier is 45 oscillated by means of a link connection 10, with a suitable actuating device. The material is fed to the needles by means of a feed dog 11, carried by a feed bar 12, which is moved back and forth by suitable mechanism 50 and which is raised and lowered by an eccentric 14 on the main shaft.

The material is held on the work support by a presser foot 16 carried by a presser bar 16^a mounted in the overhanging arm. The 55 loopers when entering the needle thread loops are moving in a direction substantially at right angles to the line of feed. After the loopers reach the forward end of their stroke, they are moved laterally for their 60 needle avoiding movements. The retracting movement of the loopers begins before the loopers complete their lateral movement, the essential feature being that the looper shall have moved over to the opposite side of the

needles from that on which the loopers pass 65 when entering the needle thread loops, prior to the time when the needles, on their return stroke pass the loopers.

Coöperating with the looper 6 is a thread retainer 17, and coöperating with the looper 70 7 is a thread retainer 18. These thread retainers are stationary and lie in planes which are substantially at right angles to the plane of the movement of the loopers as they move forward into the needle loops and, as a consequence, these retainers are substantially 75 parallel with the line of feed.

The operation of the thread retainers is thought to be obvious from the above description. In Fig. 11 of the drawings, I 80 have shown more or less diagrammatically the retainers and the loopers with which they coöperate respectively when the loopers have retracted so as to properly present the thread triangle for the needles to enter on 85 their downward movement. It will be noted that the needle thread loops have been carried by the loopers in rear of the retainers, and the retainers are operating to hold the thread loops well back on the loopers, and 90 this insures that both needles will pass into the thread triangle in advance of the needle thread loops. After the needle points are well into the thread triangle, then, of course, the needle thread loops must be released and, 95 therefore, the operative ends of the thread retainers must be set with great accuracy, so as to hold the thread loops at the right time and also release these thread loops to permit the loopers to shed the loops so that they 100 may be drawn up on the downward movement of the needles.

In accordance with one embodiment of the invention, the retainers 17 and 18 are mounted on a retainer support 19, which is secured to the apron 1^a of the work support 1. The support 19 is secured to the apron by suitable screws 20 entering threaded openings in the retainer support 19. The retainer support is provided with two openings 21 and 22. The opening 21 is for the retainer 17, while the opening 22 is for the retainer 18. Said support 19 is formed with a rearwardly projecting ledge 23. Threaded into suitable openings in the ledge is an 110 adjusting screw 24 for the retainer 17, and an adjusting screw 25 for the retainer 18. The openings 21 and 22 are each slightly larger than the shank of the retainer, as clearly shown in Fig. 6 of the drawings, and 115 the upper surface of each retainer is cut away to form a flat face 25'. The retainer 17 is held in its opening by means of a clamping screw 26, while the retainer 18 is held in its opening by a clamping screw 27. 120 125

From the above, it will be apparent that the retainer may be adjusted endwise by loosening the clamping screw and shifting

the retainer longitudinally. It may be adjusted up and down by removing the retainer and turning the adjusting screw, said screw being formed with a slot to facilitate its adjustment from above, after which the retainer is returned to its proper position and secured in place on the adjusting screw.

The throat plate of the machine is indicated at 1^b. The work support directly in front of the throat plate is formed with a recess, and the retainer support projects into this recess. It will be clear from Fig. 2 of the drawings, that the throat plate may be readily removed from the machine without disturbing this support for the retainers, so that when this throat plate is removed, the retainers are not only exposed to view but are readily accessible for adjustment, so that the operator may quickly adjust these retainers and set the same relative to the notch in the respective loopers so that they will properly engage the needle thread loops and perform their function. In other words, my improved support for the needle thread retainers permits of the adjustment of the thread retainers when they are in their normal operative position relative to the loopers.

In Figs. 7 and 8, I have shown a slightly modified form of support for the thread retainers wherein the thread retainers are mounted on a bracket 28, which in turn is mounted on the bed plate 29 of the machine. Said bracket is secured to the bed plate by suitable screws 30, and the retainers are secured to the bracket 28 in the same manner as described above in connection with the support for the retainers attached to the apron of the work support.

In Figs. 9 and 10, I have shown a further modified form of the invention wherein the retainer support is adapted to a cylindrical work supporting arm. In these views, the loopers are indicated at 6 and 7 and the retainers at 17 and 18. These retainers are clamped to a bracket 31 by means of suitable screws 32 and 33, respectively. The bracket is curved to conform with the inner wall of the cylindrical work support and is clamped thereto by means of screws 34 and 35. The throat plate is indicated at 36 in these figures of the drawings, and it will be readily seen that this throat plate may be removed without disturbing the support for the retainers. The throat plate is formed with an opening 37 through which access to the adjusting screws 32 and 33 may be had, if desired. Referring more particularly to Fig. 11, the looper threads for the respective loopers are indicated at 7, the needle threads of the needles 4—4 at 4^a and the needle threads of the needles 5—5 at 5^a. The cut away portion of the looper 6 is indicated at 6^a and the cut away portion of the looper 7

is indicated at 7^a. This figure shows the retainers 17 and 18 overlapping the loopers 6 and 7, respectively, holding the needle loops well back on the loopers in the cut away portions 6^a and 7^a respectively, so as to permit the needles on their descent to enter between the looper thread 7 and the body of the respective loopers with which said needles coöperate and at a point well in advance of the needle loops.

It will be apparent from the above description that the invention as embodied in a support for a retainer which coöperates with the looper consists in constructing the support for the retainer so that the throat plate may be readily removed without disturbing the position of the stationary retainer relative to the looper and so that not only the adjusting means for the retainer are accessible but the operator may view the active end of the retainer and its relation to the looper as the adjustment of the retainer is brought about. While I have described in detail the retainer as used in connection with the looper, it will be understood that the invention broadly consists in the supporting of a stationary thread retainer relative to any one of the stitch-forming elements in such a manner that not only the adjusting means may be readily accessible, but so that the operative end of the retainer may be viewed as the adjustment is brought about.

It is obvious that minor changes in the details of construction and the arrangement of parts may be made without departing from the spirit of this invention, as set forth in the appended claims.

Having thus described the invention, what is claimed as new is:—

1. The combination with a work support having a throat plate, a needle, a thread carrying looper coöoperating with the needle, of a stationary loop retainer for holding the needle loop back on the looper and at one side of the path of the needle, and means carried by the work support independent of the throat plate for supporting the thread retainer.

2. The combination with a work support having a throat plate, a needle, and a looper mounted beneath the work support and coöperating with the needle, of a stationary thread retainer for engaging the needle thread loop on the looper for holding the same at one side of the path of the needle, and means for adjustably supporting said retainer independent of the throat plate whereby said throat plate may be removed without disturbing the supporting means for the retainer.

3. The combination with a work support having a throat plate, a pair of needles arranged in a line at right angles to the line of feed, and a looper coöperating with both

of said needles, said looper having a notch formed therein for temporarily holding the needle thread loops as the looper retracts, of a stationary thread retainer cooperating with the looper and positioned relative thereto so that the looper carries the needle loops in rear of the retainer before said needle thread loops are released from the notch in the looper, and means for adjustably supporting said thread retainer independently

of the throat plate whereby the throat plate may be removed without disturbing the support for the retainer.

In testimony whereof I affix my signature, in the presence of two witnesses.

ULYSSES S. DE NURE.
